CLAIM

The ornamental design for a combined closure and
opener for a cup lid, as shown and described.

DESCRIPTION

FIG. 1 is a top plan view of a combined closure and
opener for a cup lid showing my new design;
FIG. 2 is a side elevation view thereof;
FIG. 3 is a bottom plan view thereof; and
FIG. 4 is a top-plan-perspective view thereof, the cup
shown in broken lines for illustrative purposes only.

FIG-1

FIG-4

FIG-2

FIG-3
